UNITED STATES PATENT OFFICE.

JAMES A. CHARTER, OF CHICAGO, ILLINOIS.

ENGINE.

1,127,184.

Specification of Letters Patent. Patented Feb. 2, 1915.

Application filed August 7, 1912. Serial No. 713,765.

To all whom it may concern:

Be it known that I, JAMES A. CHARTER, a citizen of the United States, residing at Chicago, in the county of Cook and State of Illinois, have invented a certain new and useful Improvement in Engines, of which the following is a specification.

This invention relates to explosive engines in which the cylinder is provided with an annular recess at its end beyond the piston, so that a cylindrical valve rotates therein and through proper ports controls the entrance of gas to and exhaust of the products of combustion from the cylinder. In the past, great difficulty and expense has been experienced in building devices of this class because of the great trouble in making foundry cores which stand up sufficiently well to form the above mentioned annular recess in the casting, thereby causing defective casting, which if usable at all, requires a large amount of machining. The same difficulty has been present in forming the water space between the inner and outer walls of the cylinder proper. Another difficulty has been that in prior devices, when the engine was used unequal expansion took place between the inner and outer walls of the cylinder, due to the difference in temperature, with consequent distortion of the cylinder bore and strain on the casting, and occasional resulting breakage. In prior constructions of this type of engine, it has been impossible to machine both the inside and outside of the cylinder wall and thereby provide for its uniform thickness of metal and consequent uniform expansion.

The object of this invention is to provide an engine of this type in which the inner cylinder wall is cast in one piece in such a form that it can be readily and easily cast and machined inside and outside, while the remaining parts necessary for the complete construction are also very simple and easily cast and finished, and all of the parts can be easily assembled and taken apart, thereby permitting cheap repairs or replacement of any particular part.

The invention further consists in features and details which will be described and claimed hereafter.

In the drawings in which similar numerals indicate the same parts throughout the different views, Figure 1 is a vertical par-

tially sectional detail view of a multiple cylinder engine having the preferred form of this invention applied thereto. Fig. 2 is a plan view on the line 2—2, of Fig. 1. Fig. 3 is an enlarged sectional detail view of the left hand cylinder shown in Fig. 1. Fig. 4 is a plan detail sectional view of a pair of cylinders showing the entrance and exhaust ports between them. Figs. 5, 6, 7, and 8 are detail views illustrating modifications which can be made in the form of castings of the various parts without departing from the broad spirit of this invention.

In the base casting or frame 10 is journaled a crank shaft 12 having oppositely disposed crank pins 14 and 16 attached to connecting rods 18 carrying pistons 20 of the usual type. Each one of these pistons is slidable vertically in one of the cylinders 22, 24, 26, and 28. Each one of these cylinders is provided with an inner tube or shell 30 having a contracted or neck portion 30^a, closed by an integral cap 30^b from which extends the lug 30^c, all make one piece, thus forming an inferior cylinder and combustion chamber 66 without any joints. As the upper parts of the shell are each successively smaller than those below it is obvious that it can be very readily cast in one piece by ordinary well known methods.

The outside surface of the cylinder walls just described is machined inside and out and made with two shoulders 32 and 34 located upon the outside of the cylinder. On shoulder 32 rests the inner wall 36 of the outer cylinder or jacket 38, there being a water space 40 formed between the inner cylinder and the jacket, and there being an annular recess between the portions 30^c of the inner cylinder and wall 36 of the outer cylinder within which annular space the cylindrical valve member 42 fits and rotates in the ordinary manner. The upper end of this valve member 42 is made with or has mounted upon it a toothed gear 44 driven through a suitable train of gears from the crank shaft 12, in the manner well known in the art, such for instance as beveled gears 46, shaft 48, and gear 50, the latter in the case and meshing with the successive gears 44 on the different valves of the device, which gears intermesh with each other when two or more cylinders are used, as here illustrated.

The outer cylinder 38 is secured to the main frame of the engine by bolts 52. On the top of this cylinder 38 is secured by bolts 54 a hollow plate 56 which is perforated so that lug 30° passes through it. Passing through this plate 56 are screws 58 which enter the portion 30° of the interior cylinder shell and thus support the entire interior cylinder 30 from the plate 56, and by adjusting the screws or bolts 58 the inner shell is made to bear tightly at the shoulder 32 against the inner wall 36 of the outer shell or casing 38, thus making a tight joint at 32 so that water within the water space 40 will not pass through the joint 32 and into the annular space occupied by the valve 42.

The inner shell may be supported by a single nut 59 as shown in Fig. 1 instead of by bolts 58. At the point where the inner shell 30 contacts with the lower inner projecting edge of the jacket 38, packing 60 is provided and held in compressed position by the V shaped walls 62 and 64, provided for the purpose on the parts held together by bolts 52, as heretofore described. This packing makes a sufficiently tight joint with the shell 30 so that water within the chamber 40 does not leak down into the base and yet the interior shell 30 can expand up and down as it may require under the action of heat within it. In other words, by supporting the inner shell from the top of the complete cylinder and providing the packing 60, the expansion of the shell 30 is allowed for at its free end and without in any way interfering with the operation of the valve mechanism.

By making the portion 30° of the cylinder substantially smaller than the portion 30 of the inner cylinder and consequently smaller than the piston, the explosion chamber 66 is made of a relatively small diameter and relatively long length so that while containing the proper volume of mixture for the engine the long, narrow intake and exhaust ports 68 may be used, thereby permitting quick opening and closing of the ports with a given angular movement of the valve 42, which is highly desirable for proper operation of the engine in accordance with modern standards.

It will be noticed that by the use of the plate 56 it is only necessary to remove it in order to immediately lift out the valve 42 for purposes of repair and cleaning. By constructing the inner shell with a jointless explosion chamber there is no danger of leakage of explosive mixture from the interior of the cylinder into any of the adjacent parts as frequently takes place in prior constructions.

Each of the cylinders of the engine is provided with a spark plug 70 entering the lug 30° and operated in the ordinary manner. The respective suction ports of the engine

are, of course, connected to one main passage 72 leading to the usual form of carburetor not shown.

Referring now to the modified constructions shown in Figs. 5 to 8 inclusive, that of Fig. 5 shows the one piece interior cylinder shell 76 cast so that when the external cylinder shell 78 is applied the whole device looks like the standard form of cylinder now in use, with a short water space 80. It will be noticed, that, the same exterior joint 32 is retained.

The structure of Fig. 6 differs from that of Fig. 3 in that the outer wall 38 is divided into two parts 82 and 84 joined by bolts 86, this for simplicity in making the outer shell casting.

The device of Fig. 7 shows a rigid connection 88 substituted for the sliding joint and packing 60, heretofore described.

In Fig. 8 is shown a modification in which the upper portion of the inner shell is provided with a plurality of lugs 90 which rest upon lugs 92, cast on the inside of wall 38, thus providing an additional support for the cylinder and reinforcing or taking part of the load off from the bolts 58. This minimizes the expansion of the upper portion 30° of the cylinder, but still permits the expansion of the portion 30 of the cylinder bore, which in practice is much longer in proportion than the portion 30° of the shell. In this figure is also shown the means for balancing valve 42, which is accomplished by providing opposite port holes 68, a slightly flattened recess 94, communicating with a small opening 96 entering the main cylinder, as shown. This space 94 is located between the inner cylinder shell portion 30° and the valve cylinder 42, and is of such a size as to equal the opening area of the two ports 68, so that gas passing through the hole 96 into this space 94 produces an equal pressure against the valve 42 and balances it. In Fig. 3 this balancing is done by the use of two slots or openings 98 placed opposite the port 68 above and below the horizontal planes which they occupy so that as the valve 42 revolves the opening 100 in the valve never registers with these ports 98. Each valve 42 travels at one quarter of the speed of the crank shaft and each valve 42 has two ports 100 opposite each other.

In Fig. 3 is shown a novel form of oiling device for conveying oil between the gears which drive the cylindrical valve and the surfaces of said valve for lubricating them. The device consists in placing in one portion of the gear a hole or passageway 101 which runs from the bottom of the gear teeth entirely through the gear to the interior circumference of the cylindrical valve, while in another position of the gear, as for instance on the opposite side, a hole 102

103 is bored from the gear teeth to a point on the outside circumference of the cylindrical valve, so that oil flowing through this hole drops upon this outside diameter and lubricates it. In accordance with ordinary practice, the chamber in which the gears 44 rotate is constantly supplied with oil, and by the use of these holes 101 and 103, just described, the oil is pumped from this 10 chamber containing the gears into contact with both the interior and exterior surfaces of the cylindrical valve, thereby lubricating it. The holes 101 and 103 may be multiplied in number as needed to properly lubricate the valve member.

Having thus described my invention what I claim as new and desire to secure by Letters Patent is—

1. In a device of the class described, an engine cylinder made up of a one piece internal shell having a space within which a piston is adapted to move, and an extension beyond it of smaller diameter and closing its end forming a combustion chamber 20 within said cylinder, an external cylinder or casing fitting over the first mentioned cylinder so as to leave an annular space between the two, and a cylindrical valve member rotatable within said annular space and 25 adapted to control the admission and ex-

haust of gas to and from the combustion chamber, said cylinders also forming a water space between them for cooling.

2. In a device of the class described, the combination of a cylinder member having ports, a rotatable valve outside the cylinder member having a port registering with the first mentioned ports, the parts also forming a space approximately opposite the ports in the cylinder between the wall of the cylinder and the valve, there being a passageway leading into the cylinder adapted to admit gas to said space with consequent balancing of the valve.

3. In a device of the class described, in combination with a cylindrical receptacle, a cylindrical member rotatable therein, a gear on said cylindrical member adapted to rotate it, an oil chamber inclosing the gear and passageways leading from the teeth of said gears to the inner and outer surfaces of said cylindrical member, for the purposes set forth.

In witness whereof, I have hereunto subscribed my name in the presence of two witnesses.

JAMES A. CHARTER.
